Application September 21, 1942, Serial No. 459,098

15 Claims. (Cl. 62—89)

This invention relates to a refrigerator. More specifically it relates to a refrigerator of the type having a relatively warm compartment and a relatively cold compartment adapted to cool the relatively warm compartment.

Refrigerators are known which are composed of a relatively warm compartment, a relatively cool compartment, and a wall therebetween having thermostatically controlled openings for controlling the cooling effect of the cold compartment upon the warm compartment. Frequently, in constructions of this sort, there is unsatisfactory cooling of the warm compartment because of stratification due to the inrush of cold air into the warm compartment immediately opposite an opening or openings in the wall between the compartments. The construction of the present application relates to means by which this disadvantage is overcome.

An object of the present invention is to provide an improved refrigerator.

A further object is to provide an improved refrigerator of the type in which the warm compartment is cooled by the cold compartment.

Another object is the provision of a thermostatically controlled means for regulating the cooling of the warm compartment of a refrigerator by a cold compartment.

Other objects will appear from the disclosure.

According to the present invention, a wall between the warm compartment and the cold compartment of a refrigerator is provided with thermostatically controlled openings for regulating the cooling. One opening is considerably above the other and is opened a considerable time before the other one is opened.

In the drawings:

Figure 1 is a sectional view through a refrigerator embodying the principles of the present invention;

Figures 2 and 3 are sectional views of the vertical wall between the warm and cold compartments of the refrigerator and showing the thermostatically controlled openings in the wall in two different positions;

Figure 4 is an elevational view of the vertical wall shown in Figures 2 and 3;

Figure 5 is a sectional view showing the lower end of the vertical wall and a modified form of closure therefor in closed position; and

Figure 6 is a sectional view similar to Figure 5 showing the closure in open position.

As shown in Figure 1, reference character 10 designates a refrigerator which includes a casing 11 having opposite sides 12 and 13, a top 14, and

5 a bottom 15. The casing is divided by a vertical wall 16 extending from the bottom 15 to a point near but slightly spaced from the top 14 and by a horizontal wall 17 extending between the side wall 12 and the vertical wall 16 in spaced relation with the bottom 15. Thus, the casing 11 is divided into three compartments: a warm compartment 18 extending from the top 14 and the bottom 15 and between the vertical wall 16 and the side 13, a cool compartment 19 extending between the top 14 and the horizontal wall 17 and between the side 12 and the vertical wall 16, and a chamber 20 between the horizontal wall 17 and the bottom 15 and between the side 12 and the vertical wall 16. The chamber 20 contains a condensing unit 21, which is operatively connected with an evaporating unit 22 positioned in the cold chamber 19. The condensing unit is connected with the evaporating unit in a way well understood in the art, but not shown, since the connection forms no part of the present invention. It is sufficient to state that refrigerating gas expanded in the evaporating unit for cooling of the cold chamber 19 is conducted to the condensing unit wherein it is again condensed to liquid form.

20 There is an opening 23 between the warm compartment 18 and the cold chamber 19 formed between the upper edge of the vertical wall 16 and the top 14 of the casing 11. The vertical wall 16 has an opening 24 located considerably above the horizontal wall 17 forming the bottom of the cold chamber 19. The opening 24 is adapted to be closed by a closure member 25 pivoted on pins carried on brackets 26a secured to the vertical wall 16 and on brackets 26b secured to the closure member 25. There is another opening 27 considerably below the opening 24 and adjacent to the horizontal wall 17. This opening is adapted to be closed by the closure member 28 pivotally mounted at each end on pins 29 carried by brackets 30 and 31 on the vertical wall 16 and the closure member 28. As will be seen from the figures, the closure member 25 and the opening 24 are of considerably greater vertical width than the closure member 28 and the opening 27. Since, as will be observed, the closure members and openings are of approximately the same horizontal width extending from one side of the vertical wall 16 to the other, the area of the opening 24 and the closure member 25 is considerably greater than that of the opening 27 in the closure member 28. The purpose of this will be described presently. Positioned above the opening 24 and secured to the vertical wall 16 within the wa-

chamber 18 is a thermostat 32 which is not shown in detail, since it forms no part of the present invention. It is sufficient to state that it is set to operate upon rise of the temperature in the warm chamber 18 to or above a predetermined point. When this takes place, the thermostat 32 rotates an arm 33 extending downwardly from the thermostat 32 and pivoted at a point 34 in a clockwise direction. The lower end of the arm 33 is connected by a short link 35 with a bracket 36 secured to one side of the closure member 25 at the opening 24. A bracket 37 is secured to the other side of the closure member 25, and to it is pivotally connected one end of a long link 38 which has a lower curved end 39 pivotally connected to a bracket 40 secured to the closure member 28 at the opening 27. Thus by virtue of the connection of the arm 33 with the closure member 25 through the short link 35 and the connection of the closure member 25 with the closure member 28 through the long link 38, the arrival of the temperature in the warm compartment 18 to or above a predetermined point is effective to cause the thermostat to move the arm 33 in a clockwise direction and thereby to swing the closure members 25 and 28 from the closed position of Figure 2 to the open position of Figure 3. It will be observed from Figures 2 and 3 that there is provided at the lower edge of the closure member 28 a member provided with a curved flange 41 extending into the warm compartment 18. When the closure member 28 moves toward an open position, it stays in contact with the curved flange 41 throughout a considerable part of its movement and thus serves to keep the opening 27 closed until it has reached the extreme position illustrated in Figure 2. The result is that the opening 24 is open a considerable time before the opening 27 is opened.

In operation of the refrigerator, articles to be kept at a low temperature, but not at an extremely low temperature, are placed in the warm compartment 18. This compartment has been termed a warm compartment because its temperature is somewhat above that of the so-called cold compartment 19 in which the evaporating unit 22 is positioned. As long as the warm compartment 18 stays below the predetermined temperature for which the thermostat 32 is set, the openings 24 and 27 are kept closed by the closure members 25 and 28, and there is only a very small flow of air between the compartments through the opening 23 at the top of the vertical wall 16. When, however, the temperature of the warm compartment 18 rises above the predetermined temperature for which the thermostat 32 is set, the arm 33 is caused to rotate in a clockwise direction, and this movement causes the closure members 27 and 28 to swing open as shown in Figure 3. As previously stated, the curved flange 41 keeps the lower opening 27 closed through most of the movement of the closure member 28, and the result is that the opening 24 is opened a considerable time before the opening 27 is opened. By this arrangement, cold air from the cold compartment 19 flows into the warm compartment 18 through the opening 24 and descends through the major part of the compartment 18 so as to be diffused into the warmer air contained therein, and a uniform cooling takes place. This has taken place to a considerable extent before the lower opening 27 has opened, the opening of which supplements the cooling action of the upper opening 24 by permitting the passage of cold air from the cold compartment 19 to the

warm compartment 18. If the opening 27 were open at the same time as the opening 24, the very cold air at the bottom of the cold compartment 19 would pass into the warm compartment 18 and drop quickly to the bottom without affecting the greater mass of air above the opening 27. Thus there would be stratification of the air in the warm compartment 18 or, in other words, separate layers of cold air and warm air and an unsatisfactory cooling. The vertical width of the opening 24 and consequently the total area of this opening are respectively considerably greater than the vertical width and the area of the opening 27 in order that there may be compensation for the greater cooling effect of the colder air passing through the opening 27. The horizontal wall 17 is provided as a base for the cold compartment 19 considerably above the base 15 of the casing 11 forming the base for the warm compartment 18 so that when the opening 27 is opened there may be diffusion to some extent of the very cold air passing through the opening 27, because of the dropping of this cold air through the portion of the warm compartment 18 from the level of the horizontal wall 17 to the bottom 15.

A shield 42 is provided opposite the opening 24 at the side toward the warm compartment 18. This shield is formed of wire members which include end pieces 43 with bent ends, as indicated in Figures 2 and 3, horizontal members 44 secured to and extending between the end pieces 43 in spaced relation to the vertical wall 16, and members 45 parallel to the members 44 but in contact with the wall 16, to which members the end pieces 43 are secured and which fasten the guard 42 to the vertical wall 16 by bent-out portions 46 through which extend bolts 47. The structure also includes members 48 shaped somewhat like the end pieces 43 and serving to brace the central portions of the longitudinal members 44. Two of the members 48 are somewhat close to one another and are near the arm 33 on opposite sides thereof. Opposite the arm 33 are longitudinal members 49 and 49a, which do not extend the full length of the guard 42 but leave a space between two members 48 through which access is allowed to the lower end of the arm 33 for connection of the short link 35 therewith. A U-shaped member 50 is secured at its lower end to the guard 42 and has a bent-out portion 51 at its upper end secured to the thermostat 32 by a bolt 52. A double U member 53 is secured to a portion of the U-shaped member 51 and extends to the wall 16. The members 50 and 53 serve to protect the arm 33.

In the modification shown in Figures 5 and 6, the lower closure member 28 has a flange 54 at the lower edge thereof so that, as the closure member 28 is moved toward open position by the link 38, the lower opening 27 is kept closed during a part of this time or, in other words, is not opened until after the upper opening 24 is opened a substantial amount. Thus the flange 54 on the lower closure member 28 serves the same purpose as the curved flange 41, as shown in Figures 2 and 3, namely, to prevent the lower opening 27 from opening until after the upper opening 24 has opened a substantial amount. The flange 54 moves over a part 55 which carries a flange 56 solely for stiffening.

It will be apparent from the foregoing description that a new and novel refrigerator construction has been provided by which openings in the wall between warm and cold compartments of

the refrigerator are thermostatically controlled and are arranged so that the upper opening opens a considerable time before the lower opening. This prevents stratification of warm and cold masses of air in the warm compartment and insures a good mixing of the warm and cold air. The bottom of the cold compartment is considerably above the bottom of the warm compartment so that, when the opening in the wall at the point adjacent the base of the cold compartment is opened, the very cold air passing from the bottom of the cold compartment into the warm compartment drops through the air in the portion of the warm compartment between the bottom of the cold compartment and the bottom of the warm compartment, and a good diffusion results in that part of the warm compartment.

The intention is to limit the invention only within the scope of the appended claims.

What is claimed is:

1. In a refrigerator comprising a first chamber adapted to be kept at a low temperature and a second chamber adapted to be kept at a considerably lower temperature than that of the first chamber and positioned adjacent the first chamber to abstract heat to maintain the first chamber at its low temperature, the combination therewith of means operable upon rise of the temperature in the first chamber above a predetermined point for first opening a first passage between the chambers and for thereafter opening a second passage between the chambers below the first passage.

2. In a refrigerator comprising a first chamber adapted to be kept at a low temperature, a second chamber adapted to be kept at a considerably lower temperature than that of the first chamber and positioned adjacent the first chamber to abstract heat to maintain the first chamber at its low temperature, and a common wall between the chambers, the combination therewith, of means operable upon rise of the temperature in the first chamber above a predetermined point for first providing a first opening in the wall and for thereafter providing a second opening in the wall below the first opening.

3. In a refrigerator comprising a first chamber adapted to be kept at a low temperature, a second chamber adapted to be kept at a considerably lower temperature than that of the first chamber and to abstract heat from the first chamber through connecting passage means between the chambers for maintaining the first chamber at its low temperature, the combination therewith of means operable upon rise of the temperature of the first chamber above a predetermined point for first opening a first passage between the chambers and for thereafter opening a second passage below the first passage and between the lower end of the second chamber and a point of the first chamber considerably above its lower end.

4. In a refrigerator comprising a first chamber adapted to be kept at a low temperature, a second chamber positioned alongside the first chamber with its bottom at a level considerably above the level of the first chamber and adapted to be kept at a temperature considerably lower than that of the first chamber and to abstract heat from the first chamber to maintain the first chamber at its low temperature, and a common wall between the chambers, the combination therewith of means operable upon rise of the temperature of the first chamber above a pre-

determined point for first opening a first passage in the common wall at a point well above the bottom of the second chamber and for thereafter opening a second passage in the common wall at a point adjacent the bottom of the second chamber.

5. In a refrigerator comprising a first chamber adapted to be kept at a low temperature, a second chamber positioned alongside the first chamber with its bottom at a level considerably above the level of the first chamber and adapted to be kept at a temperature considerably lower than that of the first chamber and to abstract heat from the first chamber to maintain the first chamber at its low temperature, a common wall between the chambers having a first opening at a level well above the bottom of the second chamber and a second opening below the first opening at a level adjacent the bottom of the second chamber and well above the bottom of the first chamber, and closures for the openings, the combination therewith, of means operable upon rise of the temperature in the first chamber above a predetermined point for opening the closure at the first opening in the wall, and means connecting the closures for causing opening of the closure at the first opening subsequently to opening the closure at the second opening.

6. In a refrigerator comprising a first chamber adapted to be kept at a low temperature, a second chamber positioned alongside the first chamber and adapted to be kept at a temperature considerably lower than that of the first chamber and to abstract heat from the first chamber to maintain the first chamber at its low temperature, a common wall between the chambers having a first opening well above the bottom of the second chamber and a second opening adjacent the bottom of the second chamber, and closure members movably mounted on the wall for the openings, the combination therewith, of means interconnecting the closures to make them jointly movable, means operable upon rise of the temperature in the first chamber above a predetermined point for moving the closures to open the openings, and flange means on the closure for the second opening cooperating with the second opening for keeping the second opening closed during a portion of the movement of the second closure and thereby to cause the first opening to be opened before the second opening.

7. In the refrigerator specified in claim 6, the bottom of the second container being considerably above the level of the bottom of the first container whereby the opening in the wall at the bottom of the second container is well above the bottom of the first container.

8. In the construction specified in claim 2, the first opening being of considerably larger area than the second opening.

9. In the construction specified in claim 3, the first passage being of considerably larger area than the second passage.

10. In the construction specified in claim 4, the first passage being of considerably greater vertical width than the second passage.

11. In the construction specified in claim 5, the first opening being of considerably greater vertical width than the second opening.

12. In the construction specified in claim 6, the first opening being of considerably greater area than the second opening.

13. In the construction specified in claim 7, the first opening being of considerably greater

vertical depth than the second opening, and the bottom of the second container being considerably above the level of the bottom of the first container, whereby the opening in the wall at the bottom of the second container is well above the bottom of the first container.

14. In a refrigerator, a casing, a vertical wall extending from top to bottom at a mid point between opposite side walls of the casing and a horizontal wall extending from the vertical wall to one side wall at a level considerably above the bottom of the casing so as to divide the casing into a first chamber extending from top to bottom of the casing and from the vertical wall to the other side wall and adapted to be kept at a low temperature, a second chamber extending from the top of the casing to the horizontal wall and from the vertical wall to the said one side wall and adapted to be kept at a temperature considerably lower than that of the first chamber and to abstract heat from the first chamber to maintain the first chamber at its low temperature, a third chamber between the horizontal wall and the bottom of the casing, a condensing unit positioned in the third chamber, an evaporation unit positioned in the second chamber, the vertical wall having a first closable opening well above the level of the horizontal wall and a second closable opening just above the level of the horizontal wall, and means operable upon rise of the temperature in

the first chamber above a predetermined point for first opening the first opening in the vertical wall and thereafter opening the second opening in the vertical wall.

15. In a refrigerator comprising a first chamber adapted to be kept at a low temperature, a second chamber positioned alongside the first chamber and adapted to be kept at a temperature considerably lower than that of the first chamber and to abstract heat from the first chamber to maintain the first chamber at its low temperature, a common wall between the chambers having a first opening well above the bottom of the second chamber and a second opening adjacent the bottom of the second chamber, and closure members movably mounted on the wall for the openings, the combination therewith, of means interconnecting the closures to make them jointly movable, means operable upon rise of the temperature in the first chamber above a predetermined point for moving the closures to open the openings, and flange means at the wall adjacent the second opening cooperating with the closure therefor for keeping the second opening closed during a portion of the movement of the second closure and thereby to cause the first opening to be opened before the second opening.
